UNITED STATES PATENT OFFICE.

FRED CRAWFORD, OF PROSSER, WASHINGTON.

GUARD-FINGER FOR MOWERS.

1,306,686.

Specification of Letters Patent. Patented June 17, 1919.

Application filed January 7, 1918. Serial No. 210,682.

To all whom it may concern:

Be it known that I, FRED CRAWFORD, citizen of the United States, residing at Prosser, in the county of Benton and State of Washington, have invented certain new and useful Improvements in Guard-Fingers for Mowers, of which the following is a specification.

This invention relates to guard fingers for 10 mowers and harvesters and has for its object the provision of a guard finger of such construction that the point may be removed when broken and a new point substituted therefor within a short space of time and 15 without requiring the provision of an entire finger. A further object of the invention is to provide an improved construction whereby the point of the guard finger and the stationary knife will coöperate to mutually 20 retain both in position.

The invention is illustrated in the accompanying drawings and consists in certain novel features which will be hereinafter first fully described and then particularly pointed out in the appended claims.

In the drawings—

Figure 1 is a perspective view of a guard finger constructed in accordance with my present invention with the stationary knife 30 in position thereon;

Fig. 2 is a central longitudinal vertical section;

Fig. 3 is a transverse section on the line 3—3 of Fig. 2;

Fig. 4 is a transverse section on the line 4—4 of Fig. 2;

Fig. 5 is a detail perspective view of the stationary knife;

Fig. 6 is a detail perspective fragmentary 40 view of the body portion of the guard finger;

Fig. 7 is a detail longitudinal section of a portion of the guard finger showing a slight modification.

45 The body 1 of the guard finger is tapered forwardly and has its rear portion provided with a horizontal plane surface 2 upon which the reciprocating cutter bar may slide and with a vertical shoulder 3 to guide said 50 bar, the rear extremity of the finger being bifurcated, as shown at 4, and constructed to be engaged by an anchor bolt whereby it is secured in the finger bar in the manner fully set forth in Letters Patent No. 55 1,239,570, granted to me September 11, 1917.

The vertical shoulder 3 of the guard fin-

ger is provided at its center with a shallow notch 5, the purpose of which will presently appear, and in the upper portion of the body 1 of the guard finger is formed a longitudinal recess or cavity 6, the rear portion of which extends below the web presenting the vertical shoulder 3 and in which the notch 5 is formed, a bridging bar 7 being thus produced. The body is also provided on its upper side at the ends of the vertical shoulder 3 with lugs or stops 8 between which the rear extremity of the stationary knife 9 fits, rocking or twisting movement of the knife being thereby prevented. The front end of the body 1 is provided with a threaded stem 10 having a flat upper side 11 which is unthreaded and is flush with the upper surface of the body, an abrupt shoulder 12 being thereby provided around the stem to serve as a stop or abutment for the point or tapered extremity 13 of the guard finger. The point 13 is constructed with a threaded socket 14 in its shoulder portion 15 which socket receives and engages the stem 10 of the body 1 and the upper wall of the said socket is smooth and slightly inclined, as shown clearly in Fig. 2, the several parts being so proportioned that when the point is turned home the inclined smooth wall of the socket will be opposed to the smooth flat face 11 of the stem so that a wedge-shaped pocket is provided to receive the tapered angular tongue 16 projecting from the front end of the stationary knife 9. The said tongue consequently serves as a key to bind the point and the stem together as will be readily understood on reference to Fig. 3 of the drawings. The point is provided with the usual guard 17 to extend rearwardly over and in spaced relation to the knife 9 and when the point is turned home its outer surface will be flush with the outer surface of the body and the shape of the combined point and body will be the same as that of the guard fingers now ordinarily employed.

The knife 9 is of such form and dimensions as to rest upon and extend entirely over the upper surface of the body 1 so that shoulders 18 will be provided, at the opposite sides of the tongue 16, which will engage the inner shoulder 15 of the point at the sides of the pocket 14 and will thereby serve to prevent relative twisting movement of the knife and the point. At its rear end, the knife is provided with a central depending retainer or latch in the form of a re-

silient plate 19 having its extremity turned forwardly, as shown at 20, so that it may pass under the bridge 7 and engage against the under side thereof and by its resiliency hold the knife against longitudinal movement, it being noted more particularly upon reference to Fig. 2 that the under side of the bridge 7 is inclined or beveled slightly upwardly and forwardly and the free extremity 20 of the latch is correspondingly shaped so that a firm binding engagement will be effected.

In Fig. 7, I have shown a slight modification of this arrangement in which the knife 21 is provided with a depending tongue 22 at its rear end to fit in the recess 5 flush with the surface 3 as in the previously described arrangement, but the extremity of the tongue 22 is turned rearwardly, as shown at 23, and rests upon the bottom of the recess 6 and is secured against longitudinal movement by a stud bolt or screw 24 inserted through the said member 23 into the body of the guard finger.

In assembling the parts the point 13 is first turned home upon the stem 10 after which the knife is slid forward so that the latch 19—20 will engage the bridge 7 and the tongue 16 will enter the pocket 14. The tongue 16 will, consequently, act as a key to secure the point 13 against all turning movement and, consequently, the point cannot be accidentally removed from the body of the finger. Should the point be broken, however, by contact with a large rock or through some other cause, the knife may be easily slid backward after which the broken point can be rotated so as to be relieved from its engagement with the threaded stem and a new point may then be quickly placed upon the finger and the knife returned to its operative position. The device is exceedingly simple in its construction and the arrangement of its parts and will serve to prolong the life of the cutting apparatus, as well as reduce the cost of up-keep. The

parts can be assembled or disassembled in a few moments and vexatious loss of time in the use of the machine will be overcome.

Having thus described the invention, what is claimed as new is:

1. In a guard finger, the combination of a body having a threaded mutilated stem at its forward end, a point having a threaded socket to engage said stem, and a knife held upon the body and having its front extremity interposed between the wall of said socket and the mutilated portion of the stem.

2. A guard finger comprising a body having a threaded stem at its front end, said stem having a flattened smooth side, a point having a socket threaded to engage said stem and having a flat smooth inclined wall to coact with the smooth flat portion of the stem to form a wedge-shaped pocket, and a knife removably held upon the body and provided at its front end with a tongue tapered to enter said pocket and thereby key the point to the body.

3. A guard finger comprising a body having a longitudinal recess and having a bridge over the rear portion of said recess provided with a shallow notch in its rear side at its center, a point removably fitted upon the front end of the body, a knife resting upon the body and said bridge and constructed at its front end to engage the point, and a retainer at the rear end of the knife fitting within the said shallow notch and extending within the said longitudinal recess.

4. A guard finger comprising a body provided at its front end with a stem, a point having a socket to detachably engage said stem, the upper portion of the stem being chordal to the socket, and a knife held upon the body and having its front extremity engaging between the chordal portion of the stem and the wall of the socket.

In testimony whereof I affix my signature.

FRED CRAWFORD. [L. S.]
